(57) **CLAIM**

The ornamental design for a combination speaker and stand for electronic device, as shown and described.

DESCRIPTION

FIG. 1 is a front, left and top perspective view of a combination speaker and stand for electronic device, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 2; and,

FIG. 10 is another front, left and top perspective view of the combination speaker and stand for electronic device in an open state.

The broken lines shown in the drawings are included for the purpose of illustrating portions of the combination speaker and stand for electronic device that form no part of the claimed design. In addition, the dot-dash broken lines in FIGS. 2 and 9 depict boundaries of the areas of the figures shown enlarged and form no part of the claimed design.
